UNITED STATES PATENT OFFICE.

WILLIAM T. McGRAW, OF DETROIT, MICHIGAN.

ACCOUNT-FILING CABINET.

Application filed February 14, 1921. Serial No. 444,799.

To all whom it may concern:

Be it known that I, WILLIAM T. McGRAW, a citizen of the United States of America, residing at Detroit, in the county of Wayne 5 and State of Michigan, have invented certain new and useful Improvements in Account-Filing Cabinets, of which the following is a specification, reference being had therein to the accompanying drawings.

10 The invention relates to filing cabinets of that type provided with a plurality of hinged trays which are stored within the cabinet in vertical position and may be successively turned down into horizontal position when 15 the cabinet is open. Each of these trays is provided with a series of pockets, in which the individual accounts or sales slips are placed, the pockets being designated by a number or other indicating character for 20 reference to an index, preferably arranged on the cover of the receptacle.

Cabinets of the general type above referred to have been heretofore constructed and the present invention consists in certain 25 improvements with particular reference; first, to the construction of the trays and the means for detachably mounting the same within the cabinet; second, the construction of the outer casing or cabinet, which is such 30 as to be easily and cheaply manufactured and to be completely fire-proof; and third, in various details of construction as herein-after set forth.

In the drawings:

35 Figure 1 is a perspective view of the cabinet in open position;

Figure 2 is a cross-section through one side of the cabinet with the trays removed;

Figure 3 is a perspective view of one of 40 the trays;

Figure 4 is a perspective view showing one of the guides in which the trays are hinged;

Figure 5 is a perspective view of a portion of one of the trays.

A is the outer casing or cabinet, which is formed with sides B and B', back C, a hinged top D, and a hinged front E, the latter forming, when turned in horizontal position, a desk or support for the trays F. The margin of each tray is reinforced by edge strips J, preferably of channel section which are attached to each other and to the portion G, preferably by spot-welding. For 50 holding the sales slips, clips K are provided, each consisting of a securing portion K'

which is spot-welded or otherwise secured to the bottom of the tray, and a tongue portion K² hinged to the portion K' and resiliently pressed toward the tray by a spring K³. 60 The clips K are placed in pockets on opposite sides of the tray, but are arranged to extend in opposite directions so that those on the front side, when the trays are in vertical position, will have the tongues extend 65 upward, while those on the rear side extend downward when the trays are in vertical position and inward or toward the cabinet when the trays are in horizontal position. To hold the pads from displacement in the 70 pockets having the down-turned tongues, stops L are struck out from the blank G, as indicated in Figure 3.

The trays constructed as just described are detachably mounted in the cabinet, so as 75 to be capable of swinging from vertical position to horizontal position. This is preferably accomplished by attaching to each tray adjacent to the inner edge thereof and upon opposite sides the pintles M which are 80 engageable with bearings in the sides of the casing. These bearings are preferably formed of pressed sheet metal members N which are secured to and offset from the inner faces of the cabinet sides, extending obliquely upward from front to rear. In these members N are formed the slotted bearings O for engaging the pintles and the member 85 on one side of the cabinet is also provided with entrance slots O', which extend to the edge of the member. The arrangement is such that when the pintles are engaged with the slots, the trays may be swung from vertical to horizontal position and in each position will lie in parallelism with each other. 90 The fact that the bearings are slotted permits of automatic adjustment to compensate for any differences in the two positions of adjustment or for any displacement occasioned by the thickness of the pads in the tray pockets. When in vertical position, the trays are held from accidental displacement by friction clamps P arranged upon opposite sides of the cabinet, these being preferably formed of bowed steel strips P' having 100 facing strips P² of brass or other soft metal. 105

The cabinet is formed of sheet metal with hollow walls within which are arranged fire-proof heat insulating material, such, for instance, as cellular asbestos board. Each wall 110 preferably comprises the outer and inner plates Q and Q' spaced from each other and

connected at the margin by strips Q^2 of channel section. The structure is further reinforced by channel strips R secured to the outer side and arranged parallel with the 5 margin thereof and centrally across the same.

By reason of the inclined arrangement of the members N , the trays will be arranged in stepped relation, both in horizontal and 10 in vertical positions of adjustment. This will expose index characters, which are preferably placed on sheet metal clips U secured by bending about the marginal strip of the tray. The clips are also indexed and the 15 marking is formed on sheet metal strips V which are bent about the central portion of the tongues K^2 , the edges of which are notched to receive and hold the strips from displacement.

20 The space within the cabinet beneath the trays may be utilized for storage pockets, as indicated at W , while the frame is strengthened by braces or gussets X .

One of the advantages of the construction 25 as above described is that it is made up of sheet metal parts, all of which are easily formed and are secured to each other by spot-welding. This gives strength and a fire-proof character to the cabinet, while the 30 heat insulation in the hollow walls will protect the contents of the cabinet from burning.

The engagement of the pintles M with the slots O will, as before described, permit 35 of lateral displacement of the trays, so that they will arrange themselves in parallelism, while the entrance slots O' facilitate the

quick engagement and disengagement of the trays. To avoid accidental disengagement when the trays are being disengaged, this 40 entrance slot O' intersects with the slot O intermediate the ends thereof, so that notches or recesses O^2 are formed at the outer ends of the slots O , which will hold the pintles from accidental displacement.

45 What I claim as my invention is:

1. In a filing cabinet, the combination with a casing, of a series of trays arranged within said casing in stepped relation, pintles projecting from each tray forming hinged 50 members therefor and pressed sheet metal members secured to the inner walls of the casing, said members having spaced slots extending transversely thereof for engaging the pintles, and the member on one side having entrance slots extending obliquely from said spaced slots for said pintles, said entrance slots intersecting the spaced slots intermediate the ends thereof to prevent accidental disengagement of the pintles.

55 2. In a filing cabinet, the combination with a casing, of a series of trays arranged therein in stepped relation, pintles forming hinged connections for said trays, and inclined cooperating bearings secured to the 60 walls of the cabinet and having parallel inclined slots for engaging the individual pintles and permitting automatic adjustment thereof, one of said bearings having entrance slots intersecting said inclined slots 65 intermediate the ends thereof.

70 In testimony whereof I affix my signature.

WILLIAM T. McGRAW.
